US0D1034898S

(12) **United States Design Patent** (10) **Patent No.:** **US D1,034,898 S**
(45) **Date of Patent:** **** Jul. 9, 2024**

(54) **WATER PURIFIER**

(71) Applicant: **Senwater Tech. (Shanghai) CO., Ltd.,**
Shanghai (CN)

(72) Inventor: **Haijun Yang**, Shanghai (CN)

(73) Assignee: **SENWATER TECH. (SHANGHAI)**
CO., LTD., Shanghai (CN)

(**) Term: **15 Years**

(21) Appl. No.: **29/867,147**

(22) Filed: **Oct. 12, 2022**

(30) **Foreign Application Priority Data**

Jul. 7, 2022 (CN) 202230428723.7

(51) **LOC (14) Cl.** **23-01**

(52) **U.S. Cl.**

USPC **D23/209**

(58) **Field of Classification Search**

USPC D23/209, 235, 341, 358, 363-365;
D15/5

CPC B01D 46/0002; B01D 46/10; F02M 35/04;
F02M 35/10; F02M 35/024

(57) **CLAIM**

The ornamental design for a water purifier, as shown and described.

DESCRIPTION

FIG. 1 is a perspective view of the water purifier showing the design;

FIG. 2 is a front view of the water purifier showing the design;

FIG. 3 is a back view of the water purifier showing the design;

FIG. 4 is a right view of the water purifier showing the design;

FIG. 5 is a left view of the water purifier showing the design;

FIG. 6 is a top view of the water purifier showing the design;

FIG. 7 is a bottom view of the water purifier showing the design; and,

FIG. 8 is another perspective view of the water purifier showing the design.

1 Claim, 8 Drawing Sheets
